UNITED STATES PATENT OFFICE.

LEOPOLD FRANK, OF LONDON, ENGLAND.

HAND BAG AND THE LIKE.

Application filed January 2, 1924. Serial No. 684,027.

To all whom it may concern:

Be it known that I, LEOPOLD FRANK, a British subject, and resident of 7 Westmoreland Buildings, Aldersgate Street, London, E. C. 1, England, have invented certain new and useful Improvements in or Relating to Hand Bags and the like, of which the following is a specification, such as will enable others skilled in the art to which it appertains to make and use the same.

This invention relates to hand bags, wallets, bags, attaché cases and the like including small receptacles such as purses and pocket books and may be broadly described as consisting in forming a recess or equivalent in some convenient part of the bag, case or the like and providing it with a sliding or equivalent cover controlled by a spring or springs, say elastic bands, which will draw the cover over the recess or the like and close it.

The recess may be used for any small articles such as paper money and letters or powder puffs or it may, in the case of a lady's hand bag simply contain a mirror which is uncovered by pulling back the slide which can be on the inside or the outside of the bag.

The slide may be provided with a small tag or equivalent and have its edges with the elastic or the like under that part of the bag to which it is fitted so that if the slide is of the same material as the bag it is not conspicuous and when it is pulled back against the elastics it can be there held by pressure on it through the material of the bag so that one of the user's hands will hold the bag and the slide simultaneously whilst the other hand is free.

In a general way the slide will move to and fro in a straight line with an elastic band attached to each side but it may be pivotally mounted if desired. Any suitable stops may be provided to limit the movements.

The invention is particularly applicable to ladies' hand bags and for the application of mirrors to the outside thereof and it will be more especially described with reference thereto and with reference to the accompanying drawings in which:

Fig. 1 shows part of a bag *a* to which my invention is applied. This drawing shows the device in closed position.

Fig. 2 shows a like part with the slide or cover drawn back to uncover a mirror *b*

and illustrates how the thumb of the user can apply pressure through the material of the bag on to the slide to hold it in the withdrawn position.

Fig. 3 shows a bag in perspective to which the invention is applied.

Referring to Figs. 1 and 2 the opening in the bag is shown by the line *c* and the slide or cover *d* extends to the dotted line *d'*. A clearance is left under the outer material of which the bag is made and is indicated by the dotted line *e*. On each side of the slide an elastic loop is arranged as shown at *f*, *f* and by pulling the slide downwardly to uncover the mirror, these elastic bands are stretched, as seen in Fig. 2 and by applying pressure on the outside of the bag the slide can be held in the withdrawn or open position. A tag is provided at *g* to facilitate pulling the slide back.

In Fig. 3 like reference letters to those used in Figs. 1 and 2 are used for like parts.

The slide shown is adapted to move to and fro in a straight line but it will be evident that a spring or elastic-controlled slide may be operated in other ways within the scope of the invention as for example by pivoting one part, say a corner of it and adapting it to move to and fro through the arc of a circle.

What I claim is:

1. A hand receptacle such as a hand bag or an attaché case provided with an outside opening containing a mirror and furnished with a sliding cover for the opening.

2. A hand receptacle such as a hand bag or an attaché case provided with an outside opening containing a mirror and furnished with a sliding cover for the opening, said cover being provided with elastic means to removably hold it over the mirror.

3. A hand bag having an outside recess, a mirror in the recess and an elastically held slide adapted to removably cover the mirror.

4. A hand bag having an exterior opening in its cover, a slide of greater size than the opening and fitted within the cover of the bag, elastic means for removably holding the slide opposite the opening and a mirror fitted to the bag under the slide and opposite the opening.

5. In a hand receptacle such as a hand bag a mirror arranged to face outwardly in relation to the receptacle and a sliding cover elastically held over the mirror.

6. In a hand receptacle such as a hand bag the provision of a mirror and a slide acting as a cover for the same and cooperating with the bag beyond the mirror, said mirror being so arranged that by moving the slide the mirror is uncovered without opening the bag.
- 5 7. In a hand bag the provision of a mirror, an elastically-held slide adapted to cover the mirror and so arranged that by moving the slide the mirror can be used without opening the bag.
- 10 8. A hand bag the body of which is of flexible material, an opening in the outside 15 of the bag, a mirror opposite the opening,

a slide between the mirror and the opening, elastic means for removably holding the slide over the mirror, a space within the side of the bag into which the slide can be moved and in which it can be held by pressure on that part of the outside of the flexible material under which the said space is provided.

In witness whereof I have hereunto set my hand in presence of two witnesses.

LEOPOLD FRANK.

Witnesses:

CHAS. H. HUNT,
S. TIFFORD.
